P. H. Schaefer. Andre Gobron:
~~By his Atty.~~ O. P. MacEachland

UNITED STATES PATENT OFFICE.

ANDRE GOBRON, OF PARIS, FRANCE.

ACETYLENE-GAS-GENERATING LAMP.

SPECIFICATION forming part of Letters Patent No. 595,621, dated December 14, 1897.

Application filed March 15, 1897. Serial No. 627,603. (No model.)

To all whom it may concern:

Be it known that I, ANDRE GOBRON, a citizen of France, residing at 6 Cité d'Hauteville, Paris, France, have invented certain new and useful Improvements in Gas-Generating Lamps, of which the following is a specification.

My invention relates to an improved lamp especially adapted for burning the gas produced automatically by the combination of water with the carbid of calcium.

The object of the first part of my invention is to supply the water to the generator automatically and in proportion to the requirements of consumption.

The object of the second part of my invention is to provide means for regulating the pressure obtained from the generator and when the maximum pressure is exceeded to deliver the surplus gas to a supplementary burner, which burner consumes the surplus production until equilibrium of pressure and feed is completely reestablished.

The object of the third part of my invention is to provide means for connecting the water-supply to the generator with the burner-top, by which means the one cannot be acted upon independently of the other.

My invention consists in certain constructions, combinations, and arrangements of parts hereinafter particularly described and claimed, with reference to the accompanying drawings, in which—

Figure 1 is a vertical section through the central line of the lamp; Fig. 2, a similar section on line $\alpha\alpha$ of Fig. 1; Fig. 3, a horizontal section on line zz of Fig. 1; Fig. 4, a detail view of the sector-disk, and Fig. 5 a similar view of the top disk.

The body A of the lamp comprises a base A', a stand A², and a bowl A³, consisting of a metal shell, the base A' of which contains a cylindrical generator C, fitted with a screw-cover E, from which cover the generator may be removed at any time. A bell-cylinder D, of less diameter than that of stand A² to pass through the same and provide an annular space a around said cylinder, is secured centrally to the cover E and projects up into the reservoir B of the bowl A³ and into the upper part thereof to thus provide an air-chamber d' at the upper end of said cylinder a suitable distance above the water-level of

the lamp, and also a corresponding distance above the open end of a central tube D', which opens at the bottom into the upper end of the generator.

The generator C is provided with a removable dome-shaped partition C³, having perforations c therein, below which is placed a suitable quantity of carbid of calcium C', the space C² above said partition being provided to contain the gas produced in the generator and serves thus as a gasometer. The roof of the gasometer C² is padded with felt C⁴ or other absorbent material intended to collect the moisture of the gas before it passes to the burner, and the space between the generator and the shell A' is also filled with a layer of felt to protect the same. The cap-plate A⁴ of the lamp-body carries a chimney-supporting stand A⁵, and a burner F is connected by a tube F' with the gasometer C² of the generator, and a branch pipe F'' leads from the elbow of tube F' to the plug or cover F''', through which the gas may be allowed to escape directly into the atmosphere whenever it is considered necessary.

A tap G is placed in the tube F' between the cap-plate A⁴ and the burner F and is provided with a wing-handle G'', by means of which said burner is controlled from the outside. A supplementary burner-tube K surrounds the tube F' and is connected with the cap-plate A⁴ by a valve-box I of greater diameter than the tube K, and the lower portion of said box is separated from the cap-plate of the lamp by a partition I' to provide a space I³, which communicates by holes f with the pipe F' and by perforations i with the valve-box compartment I² at the base of the supplemental burner-tube.

A safety-valve S is held down over the perforations i and within the valve-box I by a spring J, the pressure of which may be regulated to hold the said valve upon its seat under ordinary pressures of gas within the generator. If the pressure within the generator increases sufficiently to lift the valve S, the gas will pass through the holes f and space I³ into the valve-box I and through the tube K and burner-holes k and is consumed at the burner.

The supply of water to the generator is effected by means of novel devices, as follows: The bell D has holes t at its lower end, which

communicate with the water-reservoir B of the lamp, and also has a hole slightly above the middle thereof to receive the nipple d of a valve-seat and pipe-coupling m, having an 5 aperture m', which connects the upper ends of twin pipes L and M, placed outside the said bell and connected at their lower ends with the cover E of the generator to pass through the same, the pipe L being fitted with a cap 10 n' and the pipe M' provided with an elbow which opens directly over the center of the generator.

The top of the tube L is provided with a 15 plug l of felt or other material suitable for intercepting the impurities of the water before its entrance into the passage m', leading to the pipe M, which supplies water to the generator. The felt plug l is held upon the end of a rod n, which passes through the tube 20 L and may be withdrawn therefrom together with the said plug by removing a cap n' from the lower end of said tube when it is desired to clean or renew the said plug when the lamp is not in use.

25 The tube M is provided at its upper part with a conical valve N, which closes the passage m' and is connected to tap G by means of a rod N', supporting the valve, having a toothed rack at its upper end and a sector-disk H' 30 supported upon the tap-spindle, by means of which the said rod is lifted and the valve is opened when the tap is turned on. The rod and valve may also be operated independently of the valve by means of a wing-handle or 35 key H, fitted upon the end of the tap-spindle and preferably formed integral with the sector-disk H', a groove g³ in said spindle, and a set-bolt h³ on the sleeve of the key H, which latter bears loosely in said groove to allow the 40 key and sector-disk to turn freely thereon and operate the rack, rod, and valve independently of the tap. The tap is connected with the sector-disk to both operate and be operated by said disk and key by means of a 45 disk G', secured to the tap to bear against the face of the sector-disk H' and be connected therewith by means of segment-blocks h' g', formed upon the adjacent faces of said disks to interlock with each other, and thus cause 50 the tap and valve-rod to be operated jointly. The segment-block h' upon the disk H' is quadrant-shaped and the segment-block g' is semicircular. The block h' therefore occupies one-quarter and the remaining portion three-quarters of the surface of the disk. The space left between the two segment-blocks permits the tap G to be opened and closed when the valve N is closed, but it does not permit the closing of the said tap when 55 the valve N is open. By this arrangement the user is obliged to shut off the delivery of the water to the generator before closing the tap.

The operation of the lamp is as follows: The generator having been supplied with carbid of calcium, water is poured into the reservoir B, through the hole of the screw-plug R, up to a level which does not exceed the

height of the tube D', which height is conveniently regulated by any suitable means. When the water passes through the holes t 70 under the bell and reaches the level of the water in the reservoir B, the lamp is ready to work. The valve N is then opened by turning the key H, the segment-blocks upon the disks G' H' at the same time opening the 75 tap G. The water traverses the plug l and falls drop by drop, its flow being checked by the porous plug l, through the pipe M and upon the carbide and combining with the same generates the acetylene gas, which passes to 80 the gasometer C² and from there to the burner F, through the tube F', and through the central tube D' to the space above the water-line and beneath the crown of the bell D, which in conjunction with the space in the upper 85 part of the generator acts as a gasometer. If the gas generates too rapidly in the generator, the pressure increases and the gas is compressed beneath the bell D and exerts a pressure upon the surface of the water contained therein, thus causing the level of the liquid to fall until it is below the nipple d of the pipes, which thus cuts off the supply of water to the generator, and any further accumulation or excessive pressure of gas causes 90 the level of the water to be forced down until the consumption at the burner relieves the pressure. If the pressure of the gas continues to increase sufficiently to overcome the adjusted pressure upon the valve S, the gas 95 passes through holes f, the tube F', and lifting the safety-valve S passes through the tube K and is burned at k around the ordinary burner. In this manner the increase of production is compensated for by an increase of 100 consumption. The generator may be used with other generating material than carbide of calcium and supplied with other fluid than water in a like manner.

I claim as my invention and desire to secure by Letters Patent—

1. A gas-generating lamp comprising a lamp-body reservoir, a generator at the base thereof, within the lamp-casing a cover-plate and absorbent pad to which the lamp is fitted, 115 a bell-gasometer having holes at its base secured to the cover-plate and a central tube extending from said plate upwardly within the gasometer-bell, a water-supply pipe connecting the latter with the generator, a burner, 120 and a gas-supply pipe connecting the said burner with the generator, substantially as described.

2. A gas-generating lamp comprising a lamp-body, a reservoir and a generator connected therewith, a liquid-supply pipe connecting the generator and reservoir, a gas-burner and gas-tube supplied from the generator, a supplemental burner-tube connected with said gas-tube and a regulating-valve 125 to control the openings in a supplemental burner-tube and gas-tube, substantially as described.

3. A gas-generating lamp comprising a com-

- bined lamp-body, a reservoir and generator, a bell-gasometer connected to the reservoir and generator, a liquid-supply pipe connecting the middle part of the gasometer, reservoir and generator, and a valve controlling the aperture of said pipe, a gas pipe and burner, a tap and a rod connecting said tap and valve, substantially as described.
4. In a gas-generating lamp the combination with the lamp-body of the reservoir, the generator, the bell-gasometer, the pipe connecting said generator and gasometer, a second parallel pipe leading to the bottom of the lamp-reservoir, and communicating therewith by a connecting-aperture, a porous plug arranged to cover said aperture, and a rod connected to said plug and passing through said parallel pipe, substantially as described.

5. In a gas-generating lamp the combination with the lamp-body of the reservoir, the generator, the gasometer, the supply-pipes therefrom respectively, to the generator and to the burner, the liquid-supply valve leading to the generator, the gas-burner, the burner-tap, a segment-disk secured thereto, and a sector-disk having a segment-block to engage with said segment, and a rack-bar connected to said liquid-supply valve, substantially as described.

In testimony whereof I have set my hand in the presence of the two undersigned witnesses.

ANDRE GOBRON.
